Su

(10) **Patent No.:** US D650,333 S
(45) **Date of Patent:** ** Dec. 13, 2011

(54) **SILICON STEEL SHEET FOR MOTOR STATOR**

(75) Inventor: **Wei-Chung Su**, Taichung (TW)

(73) Assignee: **Yen Shen Electric Ind. Co., Ltd.**,
Taichung (TW)

(**) Term: **14 Years**

(21) Appl. No.: **29/393,434**

(22) Filed: **Jun. 3, 2011**

(51) **LOC (9) Cl.** 13-01

(52) **U.S. Cl.** D13/122

(57) **CLAIM**

The ornamental design for a silicon steel sheet for motor stator, as shown and described.

DESCRIPTION

FIG. 1 is a perspective view of a silicon steel sheet for motor stator showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof; and,

FIG. 7 is a right side view thereof.

1 Claim, 4 Drawing Sheets

FIG.1

FIG. 2

FIG. 3

FIG. 4

FIG. 5

FIG. 6

FIG. 7
